[57] CLAIM

The ornamental design for flume platform for animal confinement pens, as shown and described.

DESCRIPTION

FIG. 1 is a fragmentary perspective view taken from the top, one side and one end of a flume platform for animal confinement pens showing my new design; FIG. 2 is a fragmentary perspective view taken from the bottom, side and end opposite that shown in FIG. 1; FIG. 3 is an elevational view taken from the side shown in FIG. 1; and

FIG. 4 is an elevational view taken from the side shown in FIG. 2.

The center of the platform is broken away in FIGS. 3 and 4 to indicate indeterminate length.
